UNITED STATES PATENT OFFICE.

BENZION KARFIOL, OF NEW YORK, N. Y., ASSIGNOR TO KATHIE KARFIOL,
OF SAME PLACE.

MACHINE FOR THE MANUFACTURE OF LACE-PAPER.

SPECIFICATION forming part of Letters Patent No. 461,758, dated October 20, 1891.

Application filed March 5, 1891. Serial No. 383,826. (No model.)

To all whom it may concern:

Be it known that I, BENZION KARFIOL, a citizen of the United States, residing at New York, in the county and State of New York, have invented new and useful Improvements in Machines for the Manufacture of Lace-Paper, of which the following is a specification.

This invention has for its objects to provide a novel machine for the manufacture of lace-paper and similar articles, whereby the cutting operation is effected by two cutting-rollers co-operating with a single cutting-die roller in such manner as to avoid such excessive pressure on the cutting-die roller as would distort the paper being operated upon and thereby produce defective work. These objects are accomplished in the manner and by the means hereinafter described and claimed, reference being made to the accompanying drawing, in which the figure is a sectional elevation of a machine embodying my invention.

In carrying out my invention I provide a cutting-roller A, preferably of metal, upon whose surface is formed or engraved in relief the lines and figures of the pattern to be produced on the paper or other article. The roller A is mounted upon a shaft B, which is supported along with the other rollers and shafts of the machine on a frame O. At one side of roller A is placed the metal roller C, whose periphery is plain, and which is turned on its shaft D from frictional contact with the periphery of roller A. Over the roller A is placed the metal roller E, whose periphery is also plain. The roller E is made preferably of softer metal than that of roller C. On the side of roller A opposite to roller C is placed the roller F, whose surface contains the counterpart of the pattern that is on the cutting-roller A—that is to say, its surface is sunken, containing the pattern of roller A in reverse, the rollers A and F constituting a die and counter-die. The several rollers are pressed against each other by means of screws S, which operate upon their shafts, respectively, so as to regulate the pressure with which the rollers C, E, and F bear against roller A.

In the operation of the machine the paper or other material or fabric to be cut or per-

forated is introduced between the rollers A and C and subjected to the action of the cutting or relief surface of roller A, pressing the paper against the surface of the smooth roller C, and indenting or producing on the paper more or less completely the lines and figures of the pattern-roller. The action of the rollers A and C does not complete the cutting or perforation of the paper or other article, and if much pressure is used to press the said rollers against each other for the purpose of making the cutting more complete, one result will be to stretch portions of the paper or other article at places where the relief of the pattern occurs, and thereby weaken the paper or fabric and produce thereon unseemly bulges and swellings, which make it unsalable and unmerchantable.

In order to cut or perforate the paper or fabric perfectly and avoid stretching and marring the same, I provide a second smooth-surface metal roller E, which in this example is placed over the cutting-roller A. The roller E may be made of softer metal than the metal of which roller C is made. The paper or fabric which has passed between the rollers A and C is led thence between the rollers A and E and again subjected to the action of the cutting-roller A. This second operation of the roller A upon the paper or fabric completes the operation of cutting and producing thereon the figures and outlines which are in relief on the pattern or cutting-roller A. On the passing out of the paper or fabric from between the rollers A E, the portions thereof which are necessary to be cut out therefrom to make perfect work fall to the ground, being perfectly severed by the cutting-roller from the body of the paper or fabric without requiring to be brushed out of the rollers, as is common in machines for cutting lace-paper. From the rollers A E the paper or fabric is conducted between the said roller A and the roller F, by which it is embossed with the pattern contained on the roller F in *intaglio*, the pattern or figures which are engraved or produced on the roller A being usually produced upon the roller F by forming said roller F of paper or other suitable material on which the figures and

pattern of roller A are produced by bringing them together and rolling them upon each other under suitable pressure, so as to impress on the surface of roller F in reverse 5 the figures and lines of roller A, so that on placing the paper or other article between them and turning the rollers under proper pressure the paper will be embossed with the pattern contained on the said rollers, of 10 which one roller A is the die and the other roller F is the counter-die.

The pressure with which the rollers are pressed against each other is graduated according to the judgment of the operator, and 15 the diameters and construction of the several rollers A and F are such that perfect registering is produced, so that the successive impressions of the pattern-roller A fall upon the same places on the roller F and on the 20 paper or fabric.

I do not restrict myself to the order above named in which the paper or other article is passed between the said rollers, as the embossing-roller F and the smooth rollers C or E 25 can be made to change places, so that the embossing-roller may act upon the paper before the cutting is completed.

By my improvement the cutting of the paper or other article is effected by passing it 30 between the cutting-roller and two smooth rollers, by means of which the cutting is more perfect, the paper or article is not injured, and the cutters or cutting-surface of the pattern-roller is saved from injury by the excessive pressure which would be required in cutting 35 the paper if only one roller (like C or E) were employed in presenting the paper to the action of the pattern-roller. If only one smooth roller were employed in the cutting operation, the great pressure required would 40 weaken the paper and spoil the roller and spoil the cutting-surface of the pattern in a short time, and besides would not do the work perfectly and satisfactorily. It results from 45 my invention that the rollers will last longer

and give a nice clean cutting of the paper or article operated upon.

By the employment of the two plain-surfaced cutting-rollers C E the paper is cut perfectly and clean by two distinct cutting operations, the object of which is to avoid exerting excessive pressure on the cutting-die roller A, which would distort the paper and produce defective work.

What I claim as new, and desire to secure 55 by Letters Patent, is—

1. In a machine for cutting lace-paper and similar articles, the combination, with a cutting-roller containing the pattern in sharp-edged relief, of the plain or smooth rollers C 60 and E, against which the paper is cut successively, substantially as described.

2. A machine for making lace-paper, consisting of a supporting-frame O, the embossing counter-die roller F, the plain-surfaced 65 cutting-roller C, the cutting-die roller A, interposed between the embossing counter-die roller and the plain-surfaced cutting-roller, and the subsidiary cutting-roller E, arranged above the cutting-die roller and coacting with 70 the latter to complete the cutting operation after the initial cutting has been effected by the coaction of the cutting-die roller A and the plain-surfaced cutting-roller C, substantially as and for the purpose described. 75

3. In a machine for producing lace-paper and similar articles, the combination, with a cutting-roller containing the patterns in sharp-edged relief, of the plain or smooth rollers C and E, against which the paper is 80 cut successively, and the embossing-roller F, containing the counterpart of the pattern of the cutting-roller, substantially as described.

In testimony whereof I have hereunto set my hand in the presence of two subscribing 85 witnesses.

BENZION KARFIOL.
